(57) CLAIM

The ornamental design for a tool box, as shown and described.

DESCRIPTION

FIG. 1 is a front view of an embodiment of our new design having a closed lid.

FIG. 2 is a top view thereof.

FIG. 3 is a right side view thereof.

FIG. 4 is a back view thereof.

FIG. 5 is a perspective view thereof.

FIG. 6 is a right side view thereof.

FIG. 7 is a bottom view thereof; and,

FIG. 8 is another perspective view of the illustrated embodiment.

The broken lines shown are for the purposes of illustrating the environment of the article only and form no part of the claimed design.

1 Claim, 8 Drawing Sheets

FIG. 1

FIG. 2

FIG. 3

FIG. 4

FIG. 5

FIG. 6
